PAGE 2

Fig. 9

Fig. 8

Fig. 7

FIG. 1 is a frontal perspective view of the beverage dispenser showing my new design;

FIG. 2 is a top plan view thereof;

FIG. 3 is a frontal elevation view thereof;

FIG. 4 is an elevational view thereof taken from the end as seen from the right of FIG. 3, the opposite end being a mirror image thereof;

FIG. 5 is a cross sectional view taken along line 5—5 in FIG. 3;

FIG. 6 is a frontal perspective view showing a modification of the beverage dispenser of FIG. 1;

FIG. 7 is a frontal elevational view thereof;

FIG. 8 is an elevational view thereof taken from the end as seen from the right of FIG. 7, the opposite end being a mirror image thereof;

FIG. 9 is a cross sectional view taken along line 9—9 in FIG. 7;

The rear of the beverage dispenser design of each embodiment is substantially flat and plain in appearance.

I claim:

The ornamental design for a beverage dispenser, substantially as shown and described.
